[57] CLAIM

A liquid colorant dispensing machine, as shown and described in the drawings.

DESCRIPTION

FIG. 1 is a perspective view of a liquid colorant dispensing machine showing my new design;

FIG. 2 is a top plan view;

FIG. 3 is a front elevational view;

FIG. 4 is a rear elevational view;

FIG. 5 is a left side elevational view;

FIG. 6 is a right side elevational view; and,

FIG. 7 is a bottom plan view thereof.

FIG. 1

FIG. 2

FIG. 3

FIG. 5

FIG. 4

FIG. 6

FIG. 7
